(57) CLAIM

The ornamental design for a string tie buckle as shown and described.

DESCRIPTION

FIG. 1 is a top perspective of a string tie buckle, showing my design;

FIG. 2 is a top view thereof;

FIG. 3 is bottom view thereof;

FIG. 4 is a side view thereof;

FIG. 5 is another side view thereof;

FIG. 6 is another side view thereof;

FIG. 7 is another side view thereof; and,

FIG. 8 is a top perspective view thereof, shown in a used condition with strings shown in broken lines.

The broken lines in the drawings illustrate portions which form no part of the claimed design.
